(57) **CLAIM**

The ornamental design for a remote control device for a video phone, substantially as shown and described.

DESCRIPTION

FIG. 1 is a perspective view of a remote control device for a video phone;

FIG. 2 is a top view of the remote control device of FIG. 1; FIG. 3 is a bottom view of the remote control device of FIG. 1;

FIG. 4 is a left side view of the remote control device of FIG. 1;

FIG. 5 is a right side view of the remote control device of FIG. 1;

FIG. 6 is a back view of the remote control device of FIG. 1; and,

FIG. 7 is a front view of the remote control device of FIG. 1. The broken lines in FIGS. 1-7 do not form any part of the claimed design and are for environmental purposes.

1 Claim, 4 Drawing Sheets
